W. H. LEWIS.
SILO DOOR HINGE.
APPLICATION FILED JULY 19, 1916.

1,256,144.

FIG. 1.

Patented Feb. 12, 1918.

William H. Lewis

Inventor

By *Geo. H. Kimmel*
Attorney

UNITED STATES PATENT OFFICE.

WILLIAM H. LEWIS, OF WESTFIELD, PENNSYLVANIA.

SILO-DOOR HINGE.

1,256,144.

Specification of Letters Patent. Patented Feb. 12, 1913.

Application filed July 19, 1912. Serial No. 116,135.

To all whom it may concern:

Be it known that I, WILLIAM H. LEWIS, a citizen of the United States, and resident of Westfield, in the county of Tioga and State of Pennsylvania, have invented certain new and useful Improvements in Silo-Door Hinges, of which the following is a specification.

The present invention relates to new and useful improvements in silo doors and the like and has for its primary object the provision of new and improved hinge means for silo doors and the like.

Another object of my invention is to provide means for permanently hinging a silo door to a silo in such a manner that the hinge is not exposed to the contents of the silo which latter are usually moist, tending to rust the ordinary hinge, and one which will permit free inward movement of the silo door to permit access to the interior of the silo.

A further object of my invention is to provide a hinge for use in connection with silo doors and the like which permits a firm engagement of the closure member with the opening in the silo, the hinge swinging the closure member entirely clear of the wall of the silo and the opening therein when in open position, thereby permitting free access to the interior of the silo. The hinge of my invention is arranged in such a manner that when the door is in closed position the hinge is located exteriorly of the silo and free from contact with the contents thereof.

Other objects and advantages to be derived from the use of my improved silo door hinge will appear from the following detail description and the claim, taken with an inspection of the accompanying drawing, in which:

Figure 1 is a perspective view of a portion of a silo and door showing my improved hinge; and

Fig. 2 is a fragmental horizontal sectional view of the same.

Referring more particularly to the drawing, wherein similar characters of reference designate like and corresponding parts throughout the various views. 1 designates the wall of a silo having the usual opening 2 therein, which in the present instance is rectangular and is closed by a closure member 3 having a marginally enlarged portion 4 engaging the edges of the opening 2 as indicated at 5 in Fig. 2.

The hinge of my invention includes two pivotally connected sections pivotally mounted on the wall and closure, respectively. The wall member is substantially U-shaped and is formed with a shaft portion 6 mounted in bearings 7 secured to the wall 1 by means of screws 8 or the like. The free ends of the shaft portion 6 are bent to form laterally extending arms 9, said arms 9 being in turn right-angularly bent to form connection extensions 10, the ends of which are bifurcated as at 11 for a purpose which will hereinafter appear.

The closure section of the hinge is substantially U-shaped and is formed with a shaft portion 12 mounted in bearings 13 secured to the door 3 by means of screws 14 or the like. The free ends of the shaft portion 12 are laterally bent to form connection arms 15 having reduced extremities 16 for reception in the bifurcated portions of the extensions 10, said reduced portion and extensions 10 being connected by pivots 17.

In use it will be seen that when the door or closure is swung to open position the extensions 10 project entirely within the opening 2 and the pivotal connection of the arms 15, extensions 10 and the mounting of the shaft portion 12 permits the door to be folded back against the interior surface of the wall 1 entirely clear of the opening. The operation is reversed to close the door, pulling upon the extensions 10 serving to firmly seat the closure member 3 within the opening 2, as best shown in Fig. 2. It will be

seen that when the door is in closed position a ladder of sufficient strength is provided to permit climbing to the top of a silo. Of course, it is understood that a plurality of doors are arranged in superposed relation similar to the usual construction of silo. I also desire that it be understood that the particular manner of connecting the arms 10 and 16 need not be adhered to in reducing the device to actual practice, the drawing merely illustrating one manner of connecting said arms. I also desire to lay particular stress on the fact that the hinge of my invention may be applied to any of the standard types of doors now in use on silos.

From the above description taken in connection with the accompanying drawing, it is thought that a clear and comprehensive understanding of the construction, operation and advantages of my invention may be had, and while I have shown and de-

scribed the device as embodying a specific structure, I desire that it be understood that such changes may be made in said structure as do not depart from the spirit and scope of the invention as claimed.

Having thus fully described my invention, what I claim as new and desire to secure by Letters Patent, is:—

A hinge of the character described including a pair of U-shaped sections, said sections having arm portions thereon pivotally

connected, said sections being pivotally mounted on a door and outer wall, one of the sections having a shaft portion, laterally extending arms formed on the free ends of said shaft portion, the said arms being bent at right angles horizontally therewith to form extensions for a purpose specified.

In testimony whereof, I affix my signature hereto.

WILLIAM H. LEWIS.
